Fig. 4.

Fig. 5.

A hand-drawn diagram of a curved, segmented structure, possibly a model of a brain or a similar organ. The structure is composed of several thick, rounded segments. Numbered points are indicated: point 25 is at the top left, point 24 is at the top right, point 23 is on the right side, and point 22 is on the bottom right. A small triangular shape is located near point 25.

UNITED STATES PATENT OFFICE

OSCAR SCHNASER, OF MILBANK, SOUTH DAKOTA

LAMP GAUGE

Application filed January 28, 1930. Serial No. 424,116.

This invention relates to lamp gauges and an object of the invention is to provide for visible indication to the user of the supply of oil in the reservoir of the lamp.

5 Another feature of the invention is to provide a float interiorly of the fuel reservoir that utilizes the air chamber of the lamp for slidably guiding the float in same plane.

Other objects of the invention are to provide, in a manner as hereinafter set forth, 10 a device of the character referred to, which is strong, compact and durable, very simple in its method of assembling, very reliable in its operation, and comparatively inexpensive 15 to manufacture and install.

With the foregoing and other objects in view, the invention consists of a novel construction, combination and arrangement of parts as will be hereinafter more specifically 20 described and illustrated in the accompanying drawing, wherein it discloses an embodiment of the invention, but it is to be understood that changes, variations and modifications may be resorted to without departing 25 from the spirit hereunto appended.

In the drawings wherein like reference characters denote corresponding parts throughout the several views:—

Figure 1 is a side elevation of the fuel reservoir of a lamp, having a portion of the reservoir walls broken away illustrating an adaptation therewith of the device in accordance 30 with the present invention.

Figure 2 is a perspective view of the closure cap.

Figure 3 is a perspective view of the sleeve cap.

Figure 4 is a perspective view of the indicator drum and operating rod.

40 Figure 5 is a perspective view of the float.

Referring to the drawings in details, 6 indicates the reservoir of a lamp for containing the fuel supply of the lamp. The reservoir 6 rests upon a suitable base 7 and has extending through the interior of the reservoir 6 and out of the top thereof an air compartment or tube 8. It is to be understood that the tube extends above the base 7 and supplies the burner, not shown in the drawings, 45 with air or proper combustion of the fuel

on the wick of the lamp. Any conventional type of burner is used and is adapted to be supported on the top of the reservoir surrounding the tube 8 in any conventional manner. The reservoir 6 is provided with a closure plug 9 through which the fuel supply is replenished in the reservoir.

The reservoir 6, has formed integral therewith, at the marginal portions of the upper face an upstanding neck 10 the passage 60 through which is disposed vertically. The neck is circular in cross-section. A hollow cylindrical shaped cap indicated generally at 11 is open at its bottom. The side walls 12 of the cap 11 are tubular in configuration and there is formed in these side walls, extending longitudinal thereof an inverted V-shaped slot 13 which extends the major portion of the length of the side walls. A solid top wall 14 is formed integral with the upper edges 65 of the side walls and terminates in a laterally projecting flange 15. The side wall of the cap 11 is formed with a pair of openings 16, in alignment with each other and disposed on the diametrically opposite sides. The top wall 14 is provided with an opening 17, preferably of diamond shaped configuration. The cap 11 is adapted to be inserted in the neck 10 having the side wall 12 frictionally 70 abutting the inner side walls of the neck 10 and having the annular flange 15 overlapping and abutting against the upper edge of the neck whereby the cap is mounted in the reservoir 75 of the lamp.

An annular closure cap 18 is formed with 80 an annular shoulder 19 on the inner face thereof adjacent the bottom to receive the upper portion of the neck 10 and abut against the flanged portion 15 of the cap 11. A transparent disc 20 is anchored in annular grooves 21 85 formed adjacent the upper edge of the closure cap 18 so that a person can look into the opening 17 and at the same time to provide a tight fit to prevent evaporation of the fuel in the reservoir.

A crescent shaped float of suitable thickness 22 has a concaved portion 23 disposed in overhanging relation to the air chamber 8 so that the float will be guided thereby in the same place. It is to be understood that the float 100

22 is slidable with respect to the chamber 8. The float 22 is adapted to rest on the fuel in the reservoir in a flat relation. On the upper face of the float 22 there is formed an upstanding bracket 24 having an opening 25 therein.

10 A drum 26 has a pair of oppositely projecting trunnions 27 secured to the opposite ends thereof along the axis of the drum. The peripheral face of the drum is marked with indicating means such as letters, or the like that will register with the opening 17 in the cap 11. The oppositely disposed trunnions 27 are journaled in the openings 16. A rod 28 15 rigidly secured at one end in the peripheral face of the drum 26 extends through the slot 13 and on the other end thereof is formed with a loop 29 that is movably engaged in the opening 25 on the bracket 24. By having the loop 20 29 movable in the opening 25 any thrust on the rod 28 is compensated for so as not to bind the trunnions 27 in the opening 16.

25 In the application of the invention, as the oil is consumed from the reservoir, the float 22 holds downwardly being guided in its movement by the tube 8 which is slidably encircled by the cavity 23 on the float. When the float moves, the rod 28 rotates the barrel 26 on its trunnions 27 thereby bringing the properly 30 calibrated indicia in registration with the opening 17 that may be viewed on the face of the transparent disc 20. It will be seen from the foregoing that the person is apprised of the amount of fuel in the reservoir without requiring access to the interior thereof.

35 It is to be understood that by describing in detail herein any particular form, structure or arrangement, it is not intended to limit the invention beyond the terms of the several 40 claims, or the requirements of the prior art.

Having described my invention, what I claim as new is:—

1. In combination with a lamp fuel reservoir, having a vertically extending air compartment, said fuel reservoir having an open neck therein, a cap extending into the neck and having an opening in its upper wall and a pair of aligned openings in its side walls, said cap further having a slot in its side wall 45 between the openings, a closure cap having diaphanous panel across its upper face supported at the upper end of the neck over the first mentioned cap, a float disposed in the reservoir in slidable abutment with the air compartment, a drum having oppositely extending trunnions journaled in said pair of openings with its axis in parallelism with the top of the cap so as to register indicia on the 50 peripheral face thereof with the yoke in the cap, a rod rigidly secured at one end to the periphery of the drum and at its other end movably coupled with the float for transmitting movement of the float to the drum.

55 2. In combination with a lamp fuel reser-

voir, having a vertically extending air compartment, said fuel reservoir having an open neck therein, a cap extending into the neck and having an opening in its upper wall and a pair of aligned openings in its side wall, said cap further having a slot in its side wall 70 between the openings, a closure cap having diaphanous panel across its upper face supported at the upper end of the neck over the first mentioned cap, a float disposed in the reservoir in slidable abutment with the air compartment, a drum having oppositely extending trunnions journaled in said pair of openings with its axis in parallelism with the top of the cap so as to register indicia on the 75 peripheral face thereof with the yoke in the cap, a rod rigidly secured at one end to the periphery of the drum and at its other end movably coupled with the float for transmitting movement of the float to the drum, said float being crescent shaped and having the concaved portion thereof slidably surrounding the air compartment.

In testimony whereof I affix my signature.

OSCAR SCHNAYER.
